UNITED STATES PATENT OFFICE.

FRANK H. MCFALL, OF ALLIANCE, OHIO, ASSIGNOR TO STEPHEN C. JESSUP, OF SALEM, OHIO.

HYDROCARBON BURNER.

Application filed May 17, 1921. Serial No. 470,337.

To all whom it may concern:

Be it known that I, FRANK H. MCFALL, a citizen of the United States, residing at Alliance, in the county of Stark and State of Ohio, have invented new and useful Improvements in Hydrocarbon Burners, of which the following is a specification.

The object of my present invention is the provision of a hydrocarbon burner for use 10 in pottery kilns with a view to affording heat in such nicely regulated manner that injury to the pottery articles being burned is effectively averted.

To the attainment of the foregoing, the invention consists in the improvement as hereinafter described and definitely claimed.

In the accompanying drawings, forming part of this specification:

Figure 1 is a side elevation of my novel burner which has been reduced to actual practice and successfully operated.

Figure 2 is a longitudinal vertical section of the burner.

Figure 3 is a horizontal section taken in the plane indicated by the line 3—3 of Figure 1.

Figure 4 is a transverse section taken in the plane indicated by the line 4—4 of Figure 1, looking toward the left.

Similar numerals of reference designate corresponding parts in all of the views of the drawings.

Among other elements my novel hydrocarbon burner comprises a casing body 1 to which is connected a pipe 2 adapted to supply air under pressure of from eight ounces to one pound. In the forward end of the casing body 1 is a threaded aperture 3, and occupying the longitudinal center of the casing body 1 and threaded in the rear wall thereof as indicated by 4 is an oil tube 5, the said tube 5 being connected at the back of the casing body 1 with a T 6, one arm of which is connected to a pipe 7 adapted to supply a low grade of crude oil under a pressure of approximately thirty-five pounds. Another arm of the T 6 receives a gland plug 8, and threaded through the said plug 8 is a needle valve 9 the point of which is disposed in a taper bore 10 in a nozzle 10^x carried in and by the forward end of the tube 5.

Threaded in the forward wall of the casing body 1 and extending forwardly therefrom is an air nozzle 11 with an inwardly

directed deflector or flange 12 around the opening 13 in its forward end. Interiorly the said air nozzle 11 is provided with fin guides 14, and it will also be noted that the said air nozzle is provided with a radial aperture 15 for the passage of a screw 16 which is headed exteriorly of the nozzle 11, as indicated by 17.

Resting and adjustable rectilinearly on the guides 14 is a tubular member 20 which 65 is of larger diameter than the tube 5 and nozzle 10^x in about the proportion illustrated and is provided with a flared forward end 21. Fixed to the rear portion of the tubular member 20 and extending rearwardly therefrom and guided in an aperture 22 in the rear wall of the casing body 1 is a handle rod 23. Manifestly through the medium of the said handle rod 23 the tubular member 20 may be adjusted longitudinally 70 to increase or diminish the distance between the forward end of the tubular member 20 and the aperture 13 in the air nozzle 11, and through the medium of the screw 16 the tubular member 20 may be effectively fixed 75 adjustably in the position in which it is desired for it to remain.

In the actual reduction to practice of my invention which has been successfully operated as hereinbefore indicated, the air nozzle 11 is four and one-half inches in length, 85 is of a diameter of three and one-half inches at its rear end, and is provided with an opening 13 that is one and one-eighth inches in diameter. This size of nozzle has been 90 found to afford the desired results while all other sizes of nozzles failed. It will also be understood that I ascribe importance to the flange 12 at the forward end of the nozzle 11 inasmuch as said flange 12 serves to deflect 95 and concentrate the air when the air is permitted to escape between the forward end of the tubular member and the deflector or flange 12, this being advantageous inasmuch as it assures thorough commingling of the 100 air and oil.

In the practical use of my novel burner, the valve 9 is opened to a very slight extent, and the air nozzle 11 and the parts therein are initially heated by subjecting the nozzle 105 to the heat of burning oil-soaked waste or other fuel. The temperature afforded by the burner at the commencement of the operation is preferably about 300° F., and the heat is gradually increased. At the com- 110

mencement of operation the oil is commingled with air at the rear end only of the tubular member 20, but this is sufficient to support combustion at the beginning of operation, both the oil and the air being heated as before stated. After the starting of the burner the screw 16 is loosened, and the tubular member 20 is retracted to a slight extent whereupon a large volume of air will be 10 permitted to pass between the forward end of the member 20 and the air nozzle 11 when the temperature afforded will be gradually increased. This gradual increase in the temperature afforded is materially advantageous 15 inasmuch as it tends to prevent injury to the pottery articles being burned in the kiln and through the medium of the rod 23 the attendant is enabled to nicely adjust the tubular member 20 and may at any time desired 20 adjustably fix the said tubular member 20: it being understood in this connection that when the screw 16 is turned inwardly the tubular member 20 will be strongly clamped between the said screw 16, on the one hand, 25 and the guides 14, on the other, Figure 4.

Notwithstanding the practical advantages of my novel hydrocarbon burner for the purpose stated, it will be apparent that the burner is simple and inexpensive in construction, is durable, and is susceptible of being readily disassembled for the cleaning of its parts, and as readily reassembled to put it into condition for use.

Having described my invention, what I 35 claim and desire to secure by Letters-Patent is:—

1. A hydrocarbon burner comprising a casing body, a pipe connected to the side of said body and adapted to supply the same with air under pressure, an air nozzle connected 40 to and extending forwardly from the casing body and having an aperture in its forward end and an inwardly directed deflector surrounding said aperture and also having interior spaced fin-like longitudinal guides, a 45 screw bearing in the wall of said air nozzle and arranged in alinement with a space be-

tween said guides, a tubular member interposed between the guides and the screw and adapted to be clamped thereby and having a forward flared open end and also having a rear open end, a handle rod connected to the tubular member and guided through the rear wall of the casing body, a tube extending through and fixed in the rear wall of the 55 casing body and having its forward portion disposed in the rear portion of the tubular member, an oil nozzle carried by the forward end of said tube and having a taper bore, a needle valve having a point for cooperation 60 with said taper bore and also having a portion exterior of the casing, and a conduit connected with the said tube and adapted to be connected with a source of crude oil supply.

2. The combination in a hydrocarbon burner of an air nozzle adapted to be connected with a source of fluid pressure supply and having an aperture in its forward end, a tube having a nozzle at its forward end 70 and adapted to be connected with a source of crude oil supply, a valve complementary to said oil nozzle, a tubular member lengthwise adjustable relatively to said tube receiving in its rear portion and spaced from 75 the oil nozzle and open at its rear end and also open at its forward end and having said end arranged to abut against the inner side of the wall about the opening in the forward end of the air nozzle, and means for adjustably positioning the said tubular member.

3. In a hydrocarbon burner, the combination with a nozzle having an opening in its forward end and also having interior fin-like longitudinal spaced guides, a screw bearing 85 in the wall of said nozzle and arranged in alinement with a space between said guides, and an endwise adjustable tubular member provided with a handle and interposed and adapted to be clamped between the fin-like 90 guides and the screw.

In testimony whereof I affix my signature.

FRANK H. McFALL.
